UNITED STATES PATENT OFFICE

LESLIE W. BARNES, OF STRATFORD, CONNECTICUT

POUCH

Application filed September 27, 1927. Serial No. 222,266.

This invention relates to a pouch, preferably constructed of rubber, or other waterproof material.

An object of the invention is to provide a pouch consisting of an article containing body, a neck adapted to be rolled, folded or creased to render the interior of the body watertight and airtight, and novel and improved means for retaining the neck in rolled, folded or creased condition.

A further object is to provide a pouch consisting of an article containing body, a neck adapted to be collapsed or flattened out and rolled, folded or creased to render the interior of the body watertight and airtight, and novel and improved means for retaining the neck in collapsed or flattened out and rolled, folded or creased condition.

A further object is to provide a pouch having closing mechanism of new, specific and peculiar construction to be described designed to perform its service of rendering the interior of the body of the pouch watertight and airtight in a wholly satisfactory and dependable manner.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the appended claims.

In the accompanying drawings forming a part of this specification,

Fig. 1 is a perspective view of a pouch having the features of the invention, the neck of the pouch being disclosed in wide open position;

Fig. 2 is a perspective view of the pouch as when closed;

Fig. 3 is an end view of the pouch as when open;

Fig. 4 is an end view as when closed; and

Fig. 5 is a sectional view as on line 5—5 in Fig. 3.

With respect to the drawings and the numerals of reference thereon, 10 denotes the pouch body, 11 the pouch neck, which is 55 preferably flexible, and 12 represents, generally, the pouch closing mechanism of the invention.

Of the pouch closing mechanism, 13 is a frame, desirably of metal, said frame consisting of a single strip of material bent to rectilinear form defining the parallel vertical walls 14 and 15, and the oblique walls 16 and 17 connecting said walls 14 and 15, the ends of the strip of material meeting each 65 other along the line 18 of the wall 14.

The wall 15, adapted to be adjacent the pouch body, is offset or up-struck to provide the hook members or flange members 19 extending from the frame 13 in direction toward said pouch body. To produce the members 19, the wall 15 is vertically slit preferably at its midwidth, is also horizontally slit at spaced apart elevations, and the material of said wall defined by said slits is bent 70 outwardly from the frame, preferably at right-angles, as at 20, and inwardly as at 21, to produce hook members or flange members which are in alignment, extend toward 75 each other, and the free vertical edges 22 of 80 which are spaced a slight distance apart. See Fig. 5.

The hook members or flange members 19 of the frame 13 are for the purposes of fixing or securing said frame to and supporting 85 said frame upon the pouch body. As will be more clear from Figs. 3, 4, and 5, a length of flexible material, desirably rubber, of width as disclosed equal to the width of the pouch body, has its opposite end portions 23 secured to the pouch body in any suitable manner, as by molding, to provide a frame retainer 24 extending in direction from top toward bottom of the pouch. The part of 90 said length of material between the secured end portions 23 is free of the pouch body and is preferably a bit slack to afford a pocket 95 between said length of material and said pouch body, the pocket having openings at 100 its opposite side edges.

It might be remarked that the pocket 25 is of dimension to nicely receive both hook members or flange members 19 of the frame 13 in such manner that the side edges of the frame retainer 24 are contiguous with or closely adjacent to the connected ends of said hook members or flange members. To insert said hook members or flange members in the side openings of the pocket 25, the 10 length of flexible material constituting the frame retainer is suitably bent or doubled up and passed through the space between the adjacent free edges of the hook members or flange members and then allowed to straighten out, as will be understood from Figs. 3, 4 and 5 and the description hereinbefore made. The frame member 13 will not, it will be obvious, become accidentally removed from the pouch body when associated with said 20 pouch body in the manner as set forth.

As will be evident from Figs. 1 to 4, when the frame member 13 is associated with the pouch body, the upper portion of said frame member is about at the jointure between the 25 pouch body and the pouch neck, the lower portion of said frame member is desirably above the bottom of the pouch body, and the oblique walls 16 and 17 connecting the vertical walls 14 and 15 slant outwardly and downwardly from the pouch body.

A pouch neck retainer 26 consists of a flat strip of material, preferably metal, bent at its opposite ends to provide an upper, resilient pouch neck engaging member 27, and 30 a lower, resilient frame engaging member 28, said members 27 and 28 being, as shown, at right-angles to the body portion of the retainer 26. The body portion of the pouch neck retainer 26 is slightly longer than the 35 measurement representing the length of a wall 14 or 15. A lug 29 struck from the body of said retainer 26; extending through a vertical elongated slot 30 in the wall 14, and bent over in direction toward said wall 14 40 as at 31, provides means for holding the retainer 26 to the frame 13 and for allowing said retainer to be slid along said frame.

Numeral 32 represents a bead about the 50 mouth of the neck of the pouch adapted to rest upon the outer portion of the oblique wall 16 of the frame 13 when the pouch neck is collapsed or flattened out and folded or creased. The pouch neck engaging member 27 is adapted to engage said pouch neck and its bead when the neck retainer 26 is slid downwardly along the frame 13. The free end of said resilient member 27 is inwardly curled as indicated at 33 so that when the 55 retainer is slid down said curled portion 33 engages the neck of the pouch on a line at or adjacent to the location of said bead, and said bead is situated and confined between said oblique wall 16 of said frame 13, and said retainer 26, its resilient member 27, and

the curled portion of said resilient member. See Figs. 2 and 4.

When the retainer 26 is slid down from its location as in Figs. 1 and 3 to location where the member 27 engages the pouch neck and its bead in the manner as stated and as disclosed in Figs. 2 and 4, the frame engaging member 28 has also moved from its position as in Figs. 1 and 3 to its position as in Figs. 2 and 4. That is to say, said resilient member 28 has snapped over upon the oblique wall 17 of the frame 13, to engage against said wall 17 with spring pressure. The free end of the member 28 is also inwardly curled as indicated at 34, said inwardly curled portion engaging said wall 17. Naturally, the retainer 26 being free to slide along the wall 14 of the frame 13, the spring pressure with which the resilient member 28 engages the oblique wall 17 determines the pressure with which the resilient member 27 engages the bead of the neck and clamps said bead to the oblique wall 16, so that said bead can be in fact fastened down under any desired spring pressure by the resilient member 27. Clearly, the retainer having been once moved to position to close the pouch neck, the parts of the closure mechanism will not become accidentally displaced. When, however, it is desired to remove the pouch neck from its fastening means, this can be readily done by flexing the retainer body portion outwardly to remove the spring member 28 away from the oblique wall 17, thus releasing the retainer to position where it can be slid along the frame 13. Slight upward sliding movement of said retainer will then move the resilient member 27 in direction away from the oblique wall 16 and release the pouch neck and its bead from clamped position.

The walls of the frame 13 are desirably suitably arranged with respect to each other to provide a way or slot 35 to snugly receive a belt whereby the pouch can be suspended upon a wearer.

What I claim is:

1. A pouch comprising an article containing body having an openable side, a frame supported upon said article containing body and including an upper surface adjacent said openable side, a lower surface in spaced relation to said openable side, and a side surface, and a member slidable along the side surface of said frame, said member including an element adapted to engage said openable side and to clamp the engaged portion of said pouch against the upper surface of said frame, and a resilient element adapted to engage the lower surface of said frame to hold said element in clamping relation against said pouch.

2. A pouch comprising an article containing body having an openable side, a frame supported upon said article containing body and including an upper surface adjacent said

openable side, a lower surface in spaced relation to said openable side, and a side surface, and a member slidable along the side surface of said frame including a resilient element 5 adapted to engage said openable side, and a resilient element adapted to be sprung over and made to engage the lower surface of said frame to thus clamp the portion of said pouch engaged by said resilient element first 10 mentioned between said first mentioned resilient element and said upper surface of said frame.

3. The combination as specified in claim 2, wherein said upper and lower surfaces of 15 said frame are obliquely disposed relatively to said side surface.

4. A pouch comprising an article containing body, a flexible neck upon said body, and means for closing the opening through said 20 neck to said body, said means comprising a frame supported upon said article containing body and including an upper surface adjacent said neck, a lower surface spaced from said neck, and a side surface, and a member 25 slidable upon said frame and having upper and lower resilient elements, said upper resilient element being adapted to engage a portion of said neck when collapsed and resting upon said upper surface, and said lower 30 resilient element being adapted to be sprung over said lower surface of said frame to resiliently fasten said upper resilient element down against said neck to thus clamp said neck in closed position between said upper 35 surface and said upper resilient element.

5. A pouch comprising an article containing body having an openable side, a strip of material secured to said pouch body to provide a pocket having side openings, a frame 40 having hook members extending into the side openings of said pocket, said frame having an upper surface, a lower surface, and a side surface adjacent said pocket, and a member 45 slidable along the side surface of said frame and having an upper and a lower resilient element, said openable side of said pouch being adapted to be collapsed and made to lie upon said upper surface of said frame, said upper resilient element being adapted to engage 50 said openable side opposite said upper surface when said openable side is collapsed and upon said upper surface, and said lower resilient element being adapted to be snapped over said lower surface of said frame to be 55 brought into resilient holding relation against said lower surface to thus resiliently clamp said openable side of said pouch between said upper resilient element and said upper surface of said frame.

6. The combination as specified in claim 5, wherein said openable side of said pouch includes a bead surrounding said openable side, and said upper and lower surfaces of 65 said frame extend obliquely and downwardly from said pouch body, said bead being adapt-

ed to lie upon the outer, lower portion of said upper surface of said frame.

7. A pouch comprising an article containing body having an openable side, a strip of material secured to said pouch body to provide a pocket having side openings, a frame 70 having hook members extending into the side openings of said pocket, said frame consisting of a single piece of material providing upper and lower surfaces and spaced apart side surfaces providing a belt slot, and a clamp member slidable along one of said side surfaces, said hook members being struck up from the other of said side surfaces of said frame.

8. The combination as specified in claim 7, wherein said clamp member includes upper and lower resilient elements, said upper resilient element being adapted to engage a portion of said pouch adjacent said openable 85 side when resting upon said upper surface of said frame, and said lower resilient element being adapted to be snapped over said lower surface of said frame to be brought into holding relation with said lower surface 90 to thus clamp said openable side of said pouch between said upper resilient element and said upper surface of said frame.

9. A pouch comprising an article containing body having an openable side, a frame 95 supported upon said body and including an upper surface adjacent said openable side and a lower surface in spaced relation to said openable side, and a side surface, and a member slidable along the side surface of said 100 frame and including an element adapted to engage said openable side and an element adapted to be passed over and made to engage the lower surface of said frame to thus clamp the portion of the pouch engaged by the 105 element first mentioned between said first mentioned element and the upper surface of the frame.

Signed at Bridgeport, in the county of Fairfield and State of Connecticut, this 30th day of August, A. D. 1927.
